CLAIM

The ornamental design for an altimeter for footwear, as shown and described.

DESCRIPTION

FIG. 1 is a perspective front view of the invention.

FIG. 2 is a perspective rear view of the invention.

FIG. 3 is a top plan view of the invention.

FIG. 4 is a front plan view of the invention.

FIG. 5 is a back plan view of the invention.

FIG. 6 is a side view of the invention; and,

FIG. 7 is a side view of the invention as attached to a shoe.
